UNITED STATES PATENT OFFICE.

ALBERT T. CHURCH, OF HIGHLAND PARK, MICHIGAN, ASSIGNOR TO CRYSTAL MACHINE COMPANY, OF DETROIT, MICHIGAN, A CORPORATION OF MICHIGAN.

OPERATING MECHANISM FOR WASHING-MACHINES.

1,214,648.

Specification of Letters Patent.

Patented Feb. 6, 1917.

Application filed August 26, 1915. Serial No. 47,415.

To all whom it may concern:

Be it known that I, ALBERT T. CHURCH, a citizen of the United States, residing at Highland Park, in the county of Wayne 5 and State of Michigan, have invented a new and useful Operating Mechanism for Washing-Machines, of which the following is a specification.

The present invention relates to driving 10 mechanism for power washing machines, and it consists in a construction wherein a wringer may be swung from an upright position of use to a downward out of the way position, together with gearing for maintaining the driving connection between a 15 fixed motor and the wringer rolls in both positions; also in driving connections of the nature stated comprising a telescopic shaft and means whereby the shaft may be 20 utilized to drive the wringer rolls in either direction or may be disconnected from the rolls without stopping the motor.

The invention also consists in the details 25 of construction shown, described and particularly pointed out in the subjoined claims.

In the drawings, Figure 1 is a fragmentary side view, parts being broken away, showing a preferred embodiment of my invention. Fig. 2 is a fragmentary plan view, 30 parts being broken away, corresponding to Fig. 1.

In the embodiment of my invention shown, 1 indicates the combined sides and bottom and 2 the ends of a tub which is 35 supported on the legs 3 in the ordinary way. Resting on open bearings 4 secured to the inner face of the ends 2 are the shafts 5 whereby a drum or barrel 6, the details of which form no part of the present invention. 40 The barrel 6 is supported, said barrel being provided with a gear 7 concentric with the shafts. The gear 7 is driven by a pinion 8, the shaft 9 of which passes through the end wall of the tub and through a bossed 45 housing or bracket 10 secured to the outer face thereof, and is extended to receive the driving pulley 12 from which a belt (not shown) leads to a suitable source of power. The housing 10 includes the annular rim 13 50 which prevents clothing and the like from coming into contact with certain gearing

hereinafter described, and, together with a perforated ear 14, constitutes a guide for a gear shifting shaft 15, the offset or crank end 16 of which is received in the annular 55 groove 17 formed in the hub of the driving pulley. Normally, the end 16 is held in the groove by a spring 18 which surrounds the crank shaft and extends between the rim 13 and a collar 19 on the shaft. A hand 60 grip 20 furnishes a convenient means for turning the shaft about its axis.

It will be understood that by merely turning the gear shifting shaft so as to slide the shaft 9 away from the drum 6 until the 65 pinion 8 is out of engagement with the gear 7, the drum may be lifted out of the tub. As the pinion 8 approaches the end of its movement away from the drum, it comes into mesh with a gear 22 carried on 70 a counter-shaft 23 which projects through the wall of the tub and the housing 10 and carries a bevel gear 24. The shaft also passes through a bearing 25 formed on the housing, and through the yoke 26 by which 75 both the bevel gear 24 and the bevel gear 28, with which it meshes, are embraced. The yoke passes through a hole in the rim 13 and forms a bearing for the shaft 29 of the gear 28, and the latter has secured there- 80 to by the pin 30 or otherwise, a tubular shaft section 31, a portion of the inner surface of which is of non-circular configuration, and slidably longitudinally therein is 85 a shaft section 32, the end 33 of which conforms to the noncircular portion of the shaft section 31. The other end of the shaft passes through bearings 34 and 35 on a gear housing 36, through the loose opposed bevel gears 38 and 39, and through the clutch 90 member 40 (non-rotatable in respect to the shaft) which may be slid by the lever 41 into engagement with either of the bevel gears at will or out of contact with both. These bevel gears mesh with the bevel gear 95 42 fixed to the shaft 43 that passes through the housing and bears in the frame 44 of the wringer. Upon the shaft 43 is also carried the wringer roll 45, between which and the roll 46 the clothes are wrung in 100 the usual way, the water being discharged back into the tub by the board 47. The

housing is normally closed by a cover 48 (Fig. 1), and the clothing of the user is prevented from becoming caught in the shaft 31—32 by a telescopic casing, one section 49 of which is rigid with the yoke 26, the other section 50 being secured to the bearing 34.

The wringer frame is pivotally supported at 51 (preferably near the outer side of the 10 frame) on brackets 52 carried by the tub, and may be swung from the full-line position to that indicated in dashed lines. When the wringer is raised, a projection 53 thereon engages a spring-pressed latch 54 on the 15 tub whereby the wringer is automatically locked in place.

It is clear that various changes may be made in the details of construction without departing from the spirit of the invention. 20 I do not, therefore, wish to be limited otherwise than as indicated by the subjoined claims.

I claim:—

1. In a machine of the class described, the 25 combination of a support, a frame mounted to swing vertically thereon, a pair of roller shafts carried by the frame, said roller shafts being arranged to turn in opposite directions, and mechanism whereby the roller 30 shafts may be connected to a source of power mounted on the support when the frame is in either of a plurality of positions in respect to the support.

2. In a machine of the class described, the 35 combination of a support, a frame mounted to swing vertically thereon, a pair of roller shafts carried by the frame, said roller shafts being arranged to turn in opposite directions, and mechanism whereby the roller 40 shafts may be connected to a source of power mounted on the support when the frame is in either of a plurality of positions in respect to the support, said mechanism including a telescopic driving shaft, the end 45 portions of which are respectively mounted to swing in reference to the axis of one of the roller shafts and in reference to the support.

3. In a machine of the class described, the 50 combination of a support, a frame mounted to swing vertically thereon, a pair of roller shafts carried by the frame, said roller shafts being arranged to turn in opposite directions, a horizontal driving shaft on the 55 support, a telescopic shaft free to swing at one end about the axis of the driving shaft and at the other end about the axis of one of the roller shafts, and gearing for connecting the telescopic shaft to the other shafts.

4. In a machine of the class described, the 60 combination of a support, a frame mounted to swing vertically thereon, a pair of roller shafts carried by the frame, said roller shafts being arranged to turn in opposite

directions, a horizontal driving shaft on the 65 support, a telescopic shaft free to swing at one end about the axis of the driving shaft and at the other end about the axis of one of the roller shafts, and gearing for connecting the telescopic shaft to the other shafts, 70 said gearing including reversing means operatively connected to the end of the telescopic shaft nearest the frame.

5. In a machine of the class described, the 75 combination of a support, a frame mounted to swing vertically thereon, a pair of roller shafts carried by the frame, said roller shafts being arranged to turn in opposite directions, a driving shaft on the support, a telescopic shaft free to swing at one end in respect to the driving shaft and free to swing at the other end about the axis of one of the roller shafts, and means for connecting the several shafts so that the telescopic shaft 80 may be driven from the driving shaft and so that the roller shafts may be driven from the telescopic shafts.

6. In a machine of the class described, the 85 combination of a support, a frame mounted to swing vertically thereon, a pair of roller 90 shafts carried by the frame, said roller shafts being arranged to turn in opposite directions, a driving shaft on the support, a telescopic shaft free to swing at one end in respect to the driving shaft and free to 95 swing at the other end about the axis of one of the roller shafts, and means for connecting the several shafts so that the telescopic shaft may be driven from the driving shaft and so that the roller shafts may be driven 100 from the telescopic shafts, said last mentioned means including reversing means associated with the end of the telescopic shaft nearest the frame.

7. In a machine of the class described, the 105 combination of a support, a frame mounted to swing vertically thereon, a pair of roller shafts carried by the frame, said roller shafts being arranged to turn in opposite directions, a driving shaft on the support, a 110 telescopic shaft free to swing at one end in respect to the driving shaft and free to swing at the other end about the axis of one of the roller shafts, and means for connecting the several shafts so that the telescopic 115 shaft may be driven from the driving shaft and so that the roller shafts may be driven from the telescopic shafts, said last mentioned means including manually operable disconnecting means associated with the end 120 of the telescopic shaft nearest the frame.

8. In a machine of the class described, the 125 combination of a support, a frame mounted to swing thereon, a pair of roller shafts carried by the frame, said roller shafts being arranged to turn in opposite directions, a driving shaft mounted on the support, and mechanism for driving the roller shafts

from the driving shaft, said mechanism including a telescopic shaft, one end of which is carried by the support and the other end by the frame.

5 9. In a machine of the class described, the combination of a support, a frame mounted to swing thereon, a pair of roller shafts carried by the frame, said roller shafts being arranged to turn in opposite directions, a driving shaft mounted on the support, and mechanism for driving the roller shafts from the driving shaft, said mechanism including a telescopic shaft, one end of which is carried by the support and the other end by the frame, said mechanism also including means for reversing the directions in which the roller shafts are driven.

10 10. In a machine of the class described, the combination of a support, a frame mounted to swing thereon, a pair of roller shafts carried by the frame, said roller shafts being arranged to turn in opposite directions, a driving shaft mounted on the support, and mechanism for driving the roller shafts from the driving shaft, said mechanism including a telescopic shaft, one end of which is carried by the support and the other end by the frame, said mechanism also including manually operable controlling means carried on the frame.

15 11. In a machine of the class described, the combination of a support, a frame mounted to swing thereon, a pair of roller shafts carried by the frame, said roller shafts being arranged to turn in opposite directions, a driving shaft mounted on the support, and mechanism for driving the roller shafts from the driving shaft, said mechanism including a telescopic shaft, one end of which is carried by the support and the other end by the frame, and a telescopic casing inclosing and protecting the telescopic shaft.

20 12. In a machine of the class described, the combination of a support, a frame mounted to swing thereon, a pair of roller shafts carried by the frame, said roller shafts being arranged to turn in opposite directions, a driving shaft mounted on the support, and mechanism for driving the roller shafts from the driving shaft, said mechanism including a telescopic shaft, one end of which is carried by the support and the other end by the frame, said mechanism also including means for reversing the directions in which the roller shafts are driven, said last mentioned means including three bevel gears, one co-axial with one of the roller shafts and the other two meshing with the first in opposed relation to each other, and clutch mechanism for driving either of the two last named gears from the telescopic shaft at will.

25 13. In a machine of the class described,

the combination of a support, a frame 65 mounted to swing thereon, a pair of roller shafts carried by the frame, said roller shafts being arranged to turn in opposite directions, a driving shaft mounted on the support, and mechanism for driving the roller 70 shafts from the driving shaft, said mechanism including a telescopic shaft, one end of which is carried by the support and the other end by the frame, and means for locking the frame in one position of adjustment 75 in respect to the support.

14. In a machine of the class described, a support, a drum driving gear adapted to rotate about a horizontal axis, a frame mounted to swing on the support about a horizontal axis, a pair of roller shafts carried by the frame, said roller shafts being arranged to turn in opposite directions, a driving shaft, and means whereby the driving shaft may drive the roller shafts or may drive the 80 drum driving gear continuously in a given direction.

15. In a machine of the class described, a support, a drum driving gear adapted to rotate about a horizontal axis, a frame mounted to swing vertically on the support, a pair of roller shafts carried by the frame, said roller shafts being arranged to turn in opposite directions, a driving shaft, and means whereby the driving shaft may drive the 90 roller shafts or may drive the drum driving gear continuously in a given direction, said last mentioned means including a telescopic shaft, one end of which is mounted on the support, the other end being carried by 100 the frame.

16. In a machine of the class described, a support, a drum driving gear adapted to rotate about a horizontal axis, a frame mounted to swing on the support about a horizontal axis, a pair of roller shafts carried by the frame, said roller shafts being arranged to turn in opposite directions, a driving shaft, means whereby the driving shaft may drive the roller shafts or may drive the drum driving gear continuously in a given direction, and means for locking the frame in a predetermined position in respect to the support.

17. In a machine of the class described, a support, a frame mounted to swing thereon from a vertical position of use to a downward out of the way position, roller shafts carried by the frame, said shafts being arranged to turn in opposite directions, a driving shaft for the roller shafts located on the support, and mechanism whereby driving connection between the driving shaft and the roller shafts is preserved as the wringer swings from one position to another.

18. In a machine of the class described, a support, a frame mounted to swing thereon

from a vertical position of use to a downward out of the way position, roller shafts carried by the frame, said shafts being arranged to turn in opposite directions, a driving shaft for the roller shafts located on the support, and mechanism whereby driving

connection between the driving shaft and the roller shafts is secured when the frame is in vertical position.

In testimony whereof I sign this specifica- 10
tion.

ALBERT T. CHURCH.
